UNITED STATES PATENT OFFICE.

THOMAS WIEGAND, OF EDMONTON, ALBERTA, CANADA.

GOLD-WASHING APPARATUS.

Application filed June 16, 1923. Serial No. 645,902.

To all whom it may concern:

Be it known that I, THOMAS WIEGAND, a subject of the King of England, residing at Edmonton, in the Province of Alberta 5 and Dominion of Canada, have invented certain new and useful Improvements in Gold-Washing Apparatus, of which the following is a specification.

This invention relates to a washing apparatus for use in connection with the washing of gold, although it is to be understood that an apparatus in accordance with this invention can be employed for any purposes wherein it is found applicable, and the invention has for its object to provide an apparatus of such class, in a manner as herein-after set forth, having means to provide for the separation of the coarse rock from the sand and fine rock when the material which is to be acted on is supplied to the apparatus, and further including means to provide for the washing out and collecting of the gold from the sand and fine rock during the travel thereof through the apparatus.

Further objects of the invention are to provide a gold washing apparatus which is simple in its construction and arrangement, strong, durable, thoroughly efficient and convenient in its use, readily assembled and comparatively inexpensive to manufacture.

With the foregoing and other objects in view, the invention consists of the novel construction, combination and arrangement of parts as hereininafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a top plan view, broken away, of a gold washing apparatus in accordance with this invention.

Figure 2 is a side elevation of a gold washing apparatus, broken away, in accordance with this invention, and further illustrating in dotted lines certain of the elements of the apparatus.

Figure 3 is an enlarged view, in longitudinal section, of one end of the apparatus.

Figure 4 is a section on line 4-4, Figure 3.

Figure 5 is a section on line 5-5, Figure 2.

Figure 6 is a section on line 6-6, Figure 3.

Figure 7 is a fragmentary view, in perspective, of one of the collecting cups.

Referring to the drawings in detail, the apparatus includes a permanently inclined trough for the passage of water, sand and fine rock, and the said trough may be of any length desired, and comprises a flat bottom formed of three sections, 1, 2 and 3, the latter is imperforate and interposed between the sections 1 and 2. The section 2 is arranged at the upper end of the trough and the section 1 at the lower end. The section 2 is of greater length than the section 1 and also of greater length than the section 3, but the section 3 is of greater length than the section 1. The section 3 is formed of an elongated flat perforated metallic plate, of less thickness than the thickness of the sections 1, 2, and each of the sections 1, 2, are rabbeted at their opposed ends, as at 4, to provide a seat for the section 3. The upper faces of the sections 1, 2 and 3, are flush with each other. The spacing of the sections 1, 2, provides what may be termed an opening 5, which has 85 extending across the top thereof the section 3. The trough further includes a pair of vertically disposed side walls 6 of the desired height, and the trough is further closed at its upper end. The lower end of 90 the trough is formed with a depending discharge member 7 for the water 8 and the material discharged from the trough by the stream of water. The water, as well as the material acted on, travels in the direction of the arrows 9, and the discharge member directs the water as it leaves the trough against a water wheel 10 for the purpose of revolving it. The water wheel is arranged in advance of the lower end of the 95 trough and will be hereininafter more specifically referred to.

The upper end of the trough is mounted upon vertically disposed supporting standards 11, only one of which is shown, and the lower end of the trough is mounted upon the outer end 12, of a receptacle 13, which is arranged below the lower portion of the trough, and the latter extends upwardly from the receptacle 13 at an inclination as 110 shown in Figure 2.

Secured to and projecting upwardly from

the upper end of the trough is a hopper 14, which has its lower end permanently opening into the upper portion of the trough and said hopper 14 is provided with a combined deflecting and separating element in the form of a perforated plate 15, which extends from the rear wall to the open front 16 of the hopper, and said plate 15 inclines downwardly from the rear wall to the open 10 front wall of the hopper. That end of the plate 15, which is arranged at the open end 16 of the hopper is positioned above the bottom of the trough. The plate 15 is provided for separating the sand and fine rock 15 from the material which is supplied to the hopper for the purpose of having the gold washed therefrom, and the separated sand and fine rock pass through the plate 15 and into the upper end of the trough, and it is 20 forced down the trough by a stream of water supplied into the hopper from a flume or other suitable supply means as indicated at 17.

Arranged forwardly of the hopper 14, 25 as well as abutting thereagainst and having the plate 15 engaging therewith, is a discharging element 18 which is of inverted V-shape and of a width to project beyond each side 6 of the trough. The forward end of 30 the element 18 is provided with a vertically disposed arresting plate 19, which conforms in contour to the shape of the element 18. When the sand and fine rock is separated from the coarse rock, the coarse rock is deflected by the plate 15 on to the element 18, 35 which discharges the coarse rock from each side of the apparatus, as indicated by the arrows 20 in Figure 1. The plate 19 prevents the coarse rock from falling into the 40 trough.

Secured to, as well as depending from the bottom of the trough, is a downwardly inclined direction pan 21, which is arranged below the section 3 of the bottom of the 45 trough, and is of greater length than said section and is so positioned as to extend above the upper and project beyond the lower end of the section 3. The bottom of the pan 21, at the upper end thereof, is secured against the lower face of the section 2, and the bottom of the pan 21, at the lower end thereof, is spaced from the section 1. The travel of water and the material carried thereby through the pan 21, is indicated by 50 the direction arrows 22. The pan 21 is arranged above the receptacle 13 and the lower end of said pan 21 extends into, as well as discharges into the top of the receptacle 13.

Secured to each side of the receptacle and 55 projecting from the end 12 of said receptacle, is a pair of supporting members 23. Holdfast devices 24 are provided for securing the members 23 to the sides of the receptacle 13. The outer end of each of the supporting members 23 has secured thereto a

bearing 25, for the shaft 26, of the water wheel 10. Each end of the water wheel 10 has a series of spaced studs or pins 27 projecting outwardly therefrom, and which are provided for the purpose of intermittently 70 actuating a pair of reciprocatory shaker arms 28, which extend through the wall 12 of the receptacle 13 and are attached to the sides of a shaker box 29, which is arranged below the forward end of the directing pan 21, so that the material received in said pan 21, from the trough will be discharged into the box 29, as shown in Figure 3. Each of the arms 27 is slidably mounted in a guide 75 30, carried by a member 23, forwardly of the wall 12, and the outer end of each of the arms 27 has a depending portion 31 arranged in the path of the studs or pins 27.

The box 28 gradually decreases in height 80 from its front to its rear end and has depending from its bottom a pair of eyes 32, to which is attached a pair of pulling springs 33, which are also secured to the wall 12 of the receptacle 13, and the springs 33 are provided for shifting the box 29 in 85 a direction opposite to the direction to which the box 29 is shifted by the arms 28.

Fixedly secured within the receptacle 13, and arranged below the box 28, as well as inclining downwardly towards the end wall 90 12 of the receptacle 13, is a directing pan 34, provided with a vertically disposed element as at 35, for pivotally connecting the box 29 therewith, as well as supporting the box 29 in spaced relation with respect to 95 said pan 34. The pan 34 is of greater length than the length of the box 29 and the material is discharged from the rear end of the box 29 and into the rear end of the pan 34.

Secured to the inner face of the end wall 105 12 of the receptacle 13, below the forward end of the pan 34, is a collecting cup 36, which is constructed of copper and having its upper face coated with mercury, as at 110 37. The opposite end wall of the receptacle 13, at a point below the cup 36, has secured therewith a collecting cup 38, similar in construction to the cup 36. Arranged within the receptacle 13, is an inclined chute 39, which extends from the cup 36 to and above the cup 38 for discharging material into the latter. The end wall 12 of the receptacle 13 is provided near its lower end with a discharge outlet 40, and leading from the cup 38 to the outlet 40 is an inclined chute 41. The chute 39, as well as the chute 41, has the upper face thereof provided with a covering 42, such as burlap or other suitable fabric, so as to retain any fine or flour gold 115 that may escape from either of the cups 36 or 38.

The buckets of the water wheel 10 are indicated at 43, and receive the stream through the discharging element 7 of the trough. The said element 7 is so set up as to direct 120 125 130

the stream into the buckets 43, of the wheels 10, thereby revolving the same, and owing to the providing of the wheel with the studs or pins 27, the arms 28 will be shifted in 5 one direction, and the shifting of the arms 28 will carry the box 29 therewith against the action of the springs 33, and when the studs or pins 27 pass clear of the arms 28, the springs 33 will come into play and shift 10 the box 29 in a direction opposite to that to which it is shifted by the arms 28 and by such arrangement a reciprocatory movement will be imparted to the box 29.

From the foregoing description taken in 15 connection with the accompanying drawings, a gold washing apparatus is set up, whereby the gold is washed from the sand and fine rock or gravel during the travel of the same through the apparatus, and although the preferred embodiment of the invention is as referred to, yet it is to be understood that changes in the details of construction can be had which will fall within the scope of the invention as claimed.

25 What I claim is:—

1. A gold washing apparatus comprising an inclined trough having its bottom perforated for a portion of its length, means arranged at the upper end of the trough and 30 acting on the material to be treated to separate the lighter from the heavier particles and supplying such lighter particles to the trough and to direct the heavier particles from the trough, a directing pan suspended from the trough and having its bottom inclining downwardly and forwardly and arranged below the perforated portion of the bottom of the trough, a receptacle positioned below said pan, a directing pan secured within said receptacle, a spring controlled shaker box arranged over and pivotally connected with the last mentioned directing pan and positioned to receive material discharged from the forward end of the first mentioned 35 directing pan, a collecting cup secured within said receptacle and positioned to receive material discharged from the forward end of the second mentioned directing pan, a conducting means leading from said cup and arranged within the receptacle, and means supported from said receptacle and operated from the discharge at the lower end of the trough to provide for the reciprocation of said shaker box.

2. A gold washing apparatus comprising an inclined trough having a portion of its bottom perforated, means arranged at the upper end of the trough and acting on the material to be treated to separate the lighter from the heavier particles and supply the lighter particles into the trough and to direct the heavier particles from the trough, a directing means arranged below the perforated portion of the bottom of said trough, a receptacle positioned below the trough, and shaking, directing, collecting and conducting means arranged within said receptacle and in operative relation with respect to each other and with the shaking means arranged in operative relation with respect to the first mentioned directing means, and means supported exteriorly of said receptacle and actuated from the discharge at the lower end of the trough to provide for the operation of said shaking means.

3. A gold washing apparatus comprising an inclined trough having a portion of its bottom perforated, means arranged at the upper end of the trough and acting on the material to be treated to separate the lighter from the heavier particles and supplying such lighter particles to the trough and to direct the heavier particles from the trough, a directing pan suspended from the trough and having its bottom inclining downwardly and forwardly and arranged below the perforated portion of the bottom of the trough, a receptacle positioned below said pan, a directing pan secured within said receptacle, a spring controlled shaker box arranged over and pivotally connected with the last mentioned directing pan and positioned to receive material discharged from the forward end of the first mentioned directing pan, a collecting cup secured within said receptacle and positioned to receive material discharged from the forward end of the second mentioned directing pan, a conducting means leading from said cup and arranged within the receptacle, and means supported from said receptacle and operated from the discharge at the lower end of the trough to provide for the reciprocation of said shaker box.

4. A gold washing apparatus comprising an inclined trough having a portion of its bottom perforated, means arranged at the upper end of the trough and acting on the material to be treated to separate the lighter from the heavier particles and supplying such lighter particles to the trough and to direct the heavier particles from the trough, a directing means arranged below the perforated portion of the bottom of said trough, a receptacle positioned below the trough, and shaking, directing, collecting and conducting means arranged within said receptacle and in operative relation with respect to each other and with the shaking means arranged in operative relation with respect to the first mentioned directing means, and means supported exteriorly of said receptacle and actuated from the discharge at the lower end of the trough to provide for the operation of said shaking means.

In testimony whereof, I affix my signature hereto.

THOMAS WIEGAND.
